BLOCK SIGNALING SYSTEM FOR RAILWAYS
AND THE LIKE

Leslie Hurst Peter and James Perrin Coley, King's Cross, London, England, assignors, by mesne assignments, to The Union Switch & Signal Company, Swissvale, Pa., a corporation of Pennsylvania

Application March 17, 1942, Serial No. 435,084
In Great Britain May 20, 1940

9 Claims. (Cl. 246—26)

This invention relates to block signaling systems for railways and the like of the kind comprising signaling instruments at each end of a section of track adapted to transmit and to indicate the usual signals so as to permit a train or vehicle to enter the section by the cooperation of the instruments and the signalmen under safety conditions.

The invention has for its object to provide an improved system of this character in which the transmission of signals requesting and permitting the entrance of the train into the section together with automatic indications of the subsequent progress of the train are effected by coded current impulses, the improved system ensuring a high degree of safety in operation and requiring only a single line circuit connecting the two signaling instruments.

According to the principal feature of the invention the transmission of each current impulse constituting a code element, except the first element of a code signal, is arranged to be dependent upon and effected by the proper transmission of the preceding code element, the indication corresponding to the code signal being only effected when the code signal has been fully completed.

The invention is illustrated by way of example in the accompanying drawings of which Figure 1 is a diagrammatic view of a section of railway track between points A and B at which apparatus arranged in accordance with one form of the invention is provided. Figure 2 is a view of the line circuit between the points A and B and its associated apparatus. Figure 3 illustrates portions of the apparatus and circuit connections at the point A of the system, the similar portions of the apparatus at point B being omitted for the sake of simplicity. Figure 4 is a view in front elevation of the signalling instrument provided at each of the points A and B, Figure 5 illustrating diagrammatically the construction and circuit connections of the signalling instrument at the point A. Figures 6, 7, 8, 9, 10, 11, 12, 13 and 14 illustrate the circuit connections of portions of the apparatus at the point A of the system. Figures 11a and 12a show release lever K and signal lever S6, respectively, together with their locking segments, the lock magnets and circuits for which are shown in Figures 11 and 12. The arrangement of signal lever S5 and its locking segment, the lock magnet and circuit for which are also shown in Fig. 12, is the same as shown in Fig. 12a for lever S6, and is therefore omitted from the drawings.

Referring now to the drawings the system il-

lustrated is adapted for the transmission between points A and B at the ends of a section of track as shown in Figure 1 of the signals "is line clear received," "line clear," "line closed," and "train on line coming." These signals when received are exhibited on a signaling instrument (illustrated in Figures 4 and 5) at each end of the section, these instruments being also adapted to exhibit the signals "line clear sent" and "train on line going." Each instrument also comprises a press button 1 for transmitting the signal "is line clear," a small signal lamp 2 for indicating the reception of this signal together with a "cancel" press button 3 for transmitting a request to cancel a previous signal and an indication lamp 4 for notifying that a cancellation operation is required. Adjacent to each of the points A and B in the section of track a short insulated section of the track AXT, BXT is provided to which current is supplied, each of these track sections being provided with a track relay XTR and YTR, respectively, which is utilised to effect the automatic transmission of a signal as will be described later.

The section of track is also provided adjacent to each of the points A and B with starter signals 5, 6, 7, 8, a release lever K provided with electric locks KK and contacts KA, KE (see Figures 11 and 11a) closed in certain positions of the release lever.

The signaling instruments at A and B are electrically connected by means of a line circuit comprising two conductors 9, 10 (or a conductor and earth return), a battery ALB and BLB respectively being provided at the two ends of the line circuit from which current is derived to produce code impulses or elements.

The apparatus at each of the points A and B also comprises a slow release master relay M, a normally de-energised relay R, a slow release relay SR for the instrument at A and a similar relay QR (not shown) at B, the release time of the relay SR being however considerably greater than the release time of the relay QR.

Connected in the line circuit at each end of the section are positive and negative line relays BL and NL, the former of which is responsive only to current of positive polarity or direction, the relay NL being similarly responsive only to current of negative polarity or direction.

The apparatus at each of the points A and B also comprises a slow acting "line closed" relay LC and a slow acting "line open" relay LO together with a chain of counting relays 2A, 2B, 3A, 3B, 4A, 4B, a set of register relays 2BS, 3BS

and 4BS for positive impulses and a similar set of register relays 2NS, 3NS and 4NS for negative impulses.

Each of the signaling instruments is also provided with a set of receiving relays ARLC, ARTOLC, ALRB, ARCR, ARLBK, ARC and ARILC of which relays ARTOLC and ARILC are of the latch type adapted to operate to their energised positions by current supplied to the upper coils of the relays and mechanically latched in these positions until released by current supplied to their lower coils.

The system also comprises at each of the points A and B a set of transmitting relays ATC, ATCR, ATLB, ATLBK, ATTOLG, ATILC, and ATLC together with certain other relays which will be referred to in describing the operation of the system. It will be understood that these relays are only shown for the point A of the system and that the corresponding relays for the other point B hereinafter referred to bear the prefix "B" instead of the prefix "A." Thus for example the relay ATC at A corresponds to a similar relay BTC at B.

Each of the codes employed consists of four code elements of which the first is invariably a positive element, the remaining elements being positive or negative so that eight codes in all can be transmitted.

The various impulse combination as regards the 2nd, 3rd and 4th impulses are allotted to the different signaling indications to be transmitted as follows:

Code elements			Signal transmitted
2nd	3rd	4th	
+	+	+	"Is line clear" from A to B and B to A.
+	-	-	"Train on line coming" from B to A and "line clear" from A to B.
-	+	+	"Line closed indication" from B to A and "train on line coming" from A to B.
-	+	-	"Line clear" from B to A and "line closed" from A to B.
-	-	+	"Line closed" from B to A and "line closed indication" from A to B.
-	-	-	"Line clear received."

The indicator portion of each of the signaling instruments at A and B is of the moving coil armature type comprising (as shown in Figure 5) an armature 11 surrounded by an energising coil 12 and rotatably mounted in a magnetic field produced between the pole pieces of a permanent magnet 13. The armature is normally retained, by means of suitable springs 14, in a central position in which a pointer 15 secured thereto indicates "line closed" and is adapted to be moved in one direction or the other. From this normal position the armature is arranged to be displaced to an extent and in a direction determined by the strength of the current traversing the armature coil 12 and the polarity of this current, respectively. When a current in the positive direction of a predetermined strength traverses the armature coil 12 the armature 11 is moved towards the right to a position in which (as shown in Figure 4) the pointer 15 indicates "line clear sent" while when this current is of considerably higher strength the armature 11 is moved to a further position in which the pointer 15 indicates "train on line coming." For a negative current of predetermined strength traversing the armature coil 12 the armature 11 is correspondingly moved in the opposite direction to a position in which the pointer 15 indicates "line clear received" or if the current is of a higher strength to a position in

which the pointer 15 indicates "train on line going." The polarity and magnitude of the current transmitted to the energising coil 12 on the armature of each instrument are dependent upon the energisation of certain relays which as regards the indication "line clear" sent from the points B or A are energised by the action of the signalman. In the case of the indication "line clear received," on the other hand, the relay controlling the supply of current to the energising coil 12 of the instrument is energised only at the conclusion of the corresponding code. The current thus supplied in both cases to the energising coil 12 of the instrument is of a predetermined lower value the circuit of the coil including under these conditions suitable resistances R1 and R2.

As regards the energising coil of the instrument giving the indication "train on line going" the indication is effected by the train itself entering the short insulated track section AXT or BXT, the indication "train on line coming" at the other point being effected by the action of the relay ARTOLC which is energised only on the completion of the corresponding code, the circuit of the energising coil 12 of the instrument under these conditions not including the resistance R1 or R2 so that the current is of a corresponding higher value. As regards the indication "line closed" in which the energising coil 12 of the instrument is not traversed by current, this is effected either under normal or in-operative conditions of the system or by the train leaving the short insulated section AXT or BXT adjacent to the points A or B.

Under normal conditions, that is to say, when the section of track is closed or blocked for traffic, the line circuit and the various relays at both ends of the section are de-energised, circuit proving relays ANPR and BNPR being latched up. The pointer 15 of each signaling instrument occupies its normal position (as shown in Figure 4) so as to give the indication "line closed." The release lever K at each end of the section is locked in its normal position.

In general the operation of the system is as follows:

The signalman at the point A or B wishing to despatch a train from this point to the other point, transmits through a relay ATILC or BTILC a code signal which when properly received effects through the energisation of a relay ARILC or BRILC the illumination of the signal lamp 2 indicating "is line clear." The signalman at the other point upon receiving this signal and if prepared to receive the train then, by operating the release lever K, transmits through a relay ATLC or BTLC a code to the other point, this code when properly received effects the energisation of a relay ALCS or BLCS causing a corresponding indication "line clear sent" to be given at his signal instrument and of a relay ARLC or BRILC causing the indication "line clear received" at the other instrument and permitting the starting signal to be operated.

The starting signal having been cleared the train then proceeds from the point A or B towards the other point and upon entering the short track section AXT or BXT effects automatically through the relay ATTOLG or BTTOLG the transmission of a code signal to the other point by causing the signal instrument there to indicate through a relay ARTOLC or BRTOOLC "train on line coming" the indication "train on line going" being caused to be given at

the point from which the train is leaving by the action of a relay ATOLG or BTOLG controlled by the entrance of a train into the insulated track section AXT or BXT.

Assuming for example that it is desired to despatch the train from A to B, the signalman at A will accordingly transmit the signal "is line clear" by pressing the corresponding button 1 on the instrument at A. A circuit is thus completed from positive through relay back contacts LO9, LC8, BLP1, ATOLG1, ARTOLC2, ATLBK3, ARLBK2, normal contact KN of release lever K, push button 1, coil of relay ATILC, relay back contacts ATC1 and ATCR1 and normally closed contacts of a "code cutout" push button 16 to negative.

Relay ATILC being thus energised completes its own stick circuit from positive, relay back contact 4B4, through wire 17 and front contact ATILC2.

Relay SR is now energised (see Figure 14) from positive through relay back contacts BLP4, NLP1 and relay front contacts ANPR4 and ATILC1 and coil of relay SR to negative.

It will be seen from Figure 14 that relay SR is similarly energised when any other of the relays ATLB, ATTOLG, etc., is energised during a code transmission.

Relay BT at the point A is now energised from positive through front contact SR2 and coil of relay BT to negative and the line circuit 9, 10 is thus positively energised from battery ALB through relay front contacts BT1, and BT2 (see Figure 2).

During the operations at A above described the relays at B remain deenergised, the proving relay BNPR (like its corresponding relay ANPR) being however latched up in its energised position.

The first positive step of the code is now transmitted to the point B in the following manner.

Relay BL at point A is energised by line current and energises repeater relay BLP through an obvious circuit.

Relay M at A (see Figure 13) is energised from positive through relay front contacts BT6 and BLP5, coil of relay M and back contact R4 to negative. At the same time, relay LC (Figure 2) is energised from positive through front contact BLP6, back contacts NLP4 and NLP1, front contact ANPR1 and coil of relay LC to negative. Two stick circuits are provided for relay LC, viz., one through front contacts ANPR5 and LC13 and the other through front contact BLP6, back contact NLP4 and front contact LC9.

Relay LC being energised, a stick circuit for relay M is completed (Figure 13) from positive through front contacts LC10, BT3, BL2 and M2.

At the point B the operation above described will have caused the relay BL to be energised which in turn energises its repeater relay (not shown but corresponding to relay BLP at A). The relay M at B will remain de-energised but relay LC at B will be energised and its second stick circuit through front contact BLP closed as above described for relay LC at A.

A circuit is now completed for relay R at B (see lower part of Figure 13) from positive, front contact LC4, back contact M4, front contact BLP2, back contact BT5 and coil of relay R to negative. A stick circuit for relay R is then completed through front contact R5.

The energisation of relay BLP at A will open the circuit of relay SR at back contact BLP4 and

relay SR will accordingly release at the end of its slow release period and will open the circuit of relay BT at contact SR2 (Figure 2). The release period of relay SR thus determines the duration of the first code impulse.

The deenergization of relay BT at A opens the line circuit at contacts BT1 and BT2 so that the relay BL will release and release relay BLP.

At the point B relays BL and BLP will similarly release.

At the point A the release of relay BLP will complete a circuit for relay LO from positive through back contacts BLP6 and NLP5, front contacts LC1 and ANPR2, coil of relay LO to negative. Relay LO being thus energized another circuit for this relay coil is completed through contact LO1 shunting contact ANPR2 while a circuit for the release or lower coil of relay ANPR is completed through front contact LO5. Relay ANPR is thus unlatched and releases completing a circuit for relay LOP from positive, front contact LO3, back contact ANPR3 and coil of relay LOP to negative. It will be noted that for the energization of relays SR, LC and LO the proving relay ANPR must be latched in its energized position to which it will have been set as will be described later.

At the point B, relay LO is energized, relay BNPR released and relay LOP energised in the same manner as that above described for the corresponding relay at point A.

At the point A a circuit is completed for energising relay 2A from positive through relay front contacts LC2, LOP2 and LO4, the continuity contacts of relays 4B, 4A, 3B, 3A and 2B, coil of relay 2A to negative.

At the point B the corresponding relay 2A is energised in a similar manner and the first code step is completed.

At the point A, the second code step begins by the completion of a circuit for energising relay BT from positive through front contacts M5 and 2A3, back contact 2B3, wire 19, front contact ATILC3 and coil of relay BT to negative. Relay BT being thus energised, relays BL and BLP at points A and B are energised as described for the first code step.

It should be noted that slow release relay LC although de-energized by the previous release of relay BLP has not released until relay BLP is again energised. In the event however of the line circuit remaining open for longer than the release period of relay LC, the release of relay LC will prevent further code transmission until relay ANPR is reset by a negative current impulse.

Similarly, slow release relay LO will not release until its release period has expired after which relay LO will release and will release relay LOP. The slow release feature of relay M will prevent its release during the interval between relays BT and BLP being de-energised and re-energised.

At point A, a circuit will now be completed for relay 2BS from positive through front contacts LOP4, LO5, LC6 and BLP3, back contact NLP3, front contact 2A5 and coil of relay 2BS to negative, a stick circuit for this relay being completed from positive through front contacts LC6, LO7 and 2BS1.

At point B relay 2BS is energised and its stick circuit completed in a similar manner.

At point A the energisation of relay 2BS completes a circuit for relay 2B from positive through front contacts LC6, LO7, 2BS2, 2A1 and coil of relay 2B to negative. The energisation of relay 2B opens the circuit for relay 2A at continuity

contact 2B1 and completes a stick circuit for relay 2B through the circuit for relay 2A.

The energisation of relay 2B and the release of relay 2A de-energises wire 19 so that relay BT is de-energised and releases relays BL and BLP.

At the point B relays BL and BLP are similarly released and the second code step is completed.

The third code step now begins by a circuit being completed for relay 3A at the point A from positive through back contacts BLP 8 and NLP 8, front contacts LC11 and LO2, back contacts BT4, NT4 and 2A2, front contact 2B2 and coil of relay 3A to negative. The circuit of relay 2B is broken at continuity contact 3A1 and relay 3A is maintained energised through a stick circuit previously maintaining relay 2B.

At the point B relay 3A is energised and its stick circuit completed in a similar manner relay 2B being de-energised. At the point A, a circuit is completed from positive through front contacts M5 and 3A4, back contact 3B4, wire 20, front contact ATILC4 and coil of relay BT to negative.

The energisation of relay BT causes the energisation of relays BL and BLP at both the points A and B.

Relays BLP being energised at points A and B, the relays 3BS at these points are then energised and their stick circuits completed in a similar manner to that above described with reference to relays 2BS, and energising and stick circuits are completed for relays 3B at both points A and B the circuits of relays 3A being broken at continuity contact 3B1.

The consequent release of relays 3A effects the release of relay BT at point A which causes the release of relays BL and BLP at both points, thus completing the third code step.

The fourth code step now begins by the energisation of a circuit for relay 4A from positive through back contacts BLP8 and NLP8, front contacts LC11 and LO2, back contacts BT4, NT4, 2A2, 2B2, 3A2 and front contact 3B2 and coil of relay 4A to negative.

Relay 4A being energised breaks at its continuity contact 4A1 the circuit for relay 3B and a stick circuit for relay 4A is completed in the manner already described.

At the point B, relay 4A is energised and its stick circuit completed and relay 3B released in the same way.

At the point A a circuit is completed from positive through front contacts M5 and 4A4, back contact 4B5, wire 21, front contact ATILC5 and relay BT to negative.

Relays BL and BLP at points A and B are thus energised as before completing energising and stick circuits for relays 4BS at both points.

A circuit is now completed at point A for relay 4B from positive through front contacts LC6, LO7 and 4BS2, back contact R8, front contacts ATILC3, 4BS9, 3BS7, 2BS5 wires 22 and 23, front contact 4A2 and coil of relay 4B to negative.

The corresponding circuit for relay 4B at point B is completed from positive through front contacts LC8, LO7, 4BS2, R8, wires 24 and 23, front contact 4A2 and coil of relay 4B to negative.

The relays 4B at points A and B being thus energised the circuits of relays 4A are broken at continuity contacts 4B1 and the stick circuits of relays 4B are completed in a similar manner to that already described for the other corresponding relays.

At the point A, the release of relay 4A breaks the circuit of relay BT at front contact 4A4 and

the relays BL and BLP at both points A and B are thus released completing the fourth and last code step.

At the point A the energisation of relay 4B breaks the stick circuit for relay ATILC at contact 4B4.

At the point B delivery relay D is energised from positive through back contacts BLP8 and NLP8, front contacts LC11 and LO2, back contacts BT4, NT4, 2A2, 2B2, 3A2, 3B2 and 4A3, front contacts 4B2 and R7 and coil of relay D to negative.

At the point A, relay LC releases after its time period breaking the circuits for relays LO, 4B and M. These relays are thus released, relay LO releasing relay LOP.

At the point B, relay LC eventually releases and relays LO and D being thus de-energised, release and release relay LOP which in turn releases relay R.

In the meantime the energisation of relay D completes a circuit for relay BRILC from positive through front contacts D3, 2BS3, wire 25, front contacts 3BS4 and 4BS6, back contact BRLBK3 normal contact KN of lever K, coil of relay BRILC, wire 26 and back contacts BTC9 and BTCR8 to negative.

Relay BRILC is thus energised and is latched up.

30 The release of relays D and LC at the point B breaks the stick circuits for the code storage relays 2BS, 3BS and 4BS which accordingly release while the release of relay LC deenergises relay 4B.

35 During the release period of relay R, that is, when relays LC, LO and LOP are deenergised but relay R has not yet released, a circuit is completed from positive through front contact R3, back contacts LC12, LO10, LOP3 and coil of relay NT to negative.

30 The energisation of relay NT at point B causes the line circuit 9, 10 to be supplied with negative current from battery BLB through contacts NT1 and NT2 and the relays NL and NLP at points A and B are thus energised.

45 At the point A the proving relay ANPR is now energised from positive through back contacts M5, R2, 2BS6, 2NS8, 3BS8, 3NS7, 4BS10, 4NS8, 4B2, D4, LOP5, LO8, LC7, front contact NLP9, the upper coil of relay ANPR to negative.

50 Relay ANPR at point A is thus energised and latched, relay BNPR at point B being similarly operated.

55 At the point B when relay R eventually releases the relay NT is deenergised and relays NL and NLP at both points are then released.

60 All the relays are now deenergised but at point B relay BRILC is latched in its energised position in response to the completion of the code signal "is line clear" sent front point A.

65 The operation of the system during the four steps of a code signal transmission having been described in detail as regards the signal "is line clear" resulting in the energisation of the corresponding relay BRILC at the point B, it will be understood that the transmission of the other code signals is effected by a similar series of relay operations at each step resulting finally in the energisation of a relay of the group in which the relay BRILC is included.

70 The complete operation of sending a train from point A to point B will now be described.

75 The signalman at A first actuated the press button 1 to effect the latching of the relay BRILC as above explained in detail. As a result the lamp

2 and a bell 21 are supplied with operating current through a circuit (see Figure 7) from positive, front contact BRILC3 and lamp 2 and bell 21 to negative.

When the signalman at B is in a position to give "line clear" to A, he reverses his release lever K, this being possible by the energisation of the normal lock KK over front contact BRILC4 (see Figure 11), providing no other code is on the line. Reversal of this lever K energises relay BTLC, provided that the coding equipment is at rest, as indicated by back contacts of relays LC, LO and BLP in the pick up circuit. The circuit may be traced (see Figure 2) from positive through back contacts LO9, LC8, BLP1, BTOLG1, BRTOLC2, BTLBK3, BRLBK2 reverse contact on lever K, front contact BRILC5 coil of relay BTLC, back contacts 1 of relays BTC, BTCR, the "code cut out" button 16 to negative.

A stick circuit for relay BTLC is completed through back contact 4B4 and front contact BTLC2. Energisation of relay BTLC energises latch coil of relay BRILC at front contact BTLC7, so releasing this relay, breaking the pick-up circuit of relay BTLC, and stopping the bell 21 which has been ringing since the "is line clear" indication lamp 2 was illuminated.

Relay BTLC will then initiate a code transmission energising relay ARLC, providing relay BRILC has released as arranged for, by back contact BRILC1 in the second step code selection circuit. It will be noted that B's release lever K is locked in the reverse position, after the release of relay BRILC, also, on completion of the "line clear" code transmission, relay BLCS is energised through a circuit (see Figure 10) including front contacts of 4B9 and BTLC9, coil of relay BLCS, back contact BTC8 to negative, and sticks up through back contact BRTOLC8 and front contact BLCS2.

At the point B, energisation of relay BLCS connects positive to the instrument at front contact BLCS4, through resistance R1, coil 12 of the instrument, resistance R2, back contact BRLCP4, and front contact BLCS3 to negative, thus moving the instrument to "line clear sent."

Relay ARLC sticks up through an obvious stick circuit provided that both the starting signals are at "danger" as determined by contacts NB of the levers controlling these signals. Relay ARLCP (see Figure 6) now picks up, through a circuit including front contact ARLC3, and sticks up over back contact ATTOLG7 and front contact ARLCP3.

Energization of relay ARLCP connects positive to the instrument over front contact ARLCP4 resistance R2, coil 12 of the instrument, resistance R1, and over front contact ARLCP5 to negative, the instrument thus moving to "line clear received."

Operation of one of the starting signals releases relay ARLC by breaking the stick circuit at the contacts NB, but picks up relay 6/5SS through a circuit including front contact ARLCP2. An obvious stick circuit including front contact 6/5SS2 is then completed.

Nothing further occurs until the train passes the starting signal 5 or 6 and de-energises the fouling track circuit AXT. The corresponding track relay XTR releasing, picks up relay ATTOLG, over front contact 6/5SS2 and back contact XTR1 of the track relay. When relay ATTOLG picks up, relay ARLCP is released, as the stick circuit is broken at back contact 7. In addition, relay 6/5SS is released, as the re-

turn circuit is broken at front contact ARLCP2. It will be seen that the release of relays ARLCP and 6/5SS are checked in the transmission code selection for the second impulse at back contacts ARLCP1 and 6/5SS3. When this transmission is complete, relay ATOLG picks up (see Figure 10) over front contacts relay 4B9 and ATTOLG9 and latches.

Referring again to Figure 5 it will be seen that relay ATOLG connects positive direct on to the instrument at front contact ATOLG3, and negative at front contact ATOLG4, thus moving the instrument to "train on line going."

The starting signals can now be replaced.

Receiving relay BRTOLC picks up and latches up in response to the transmission initiated by relay ATTOLG, and relay BRTOLC opens the stick circuit for relay BLCS (see Figure 10) at back contact BRTOLC8. In addition positive energy is applied to the instrument at B through front contact BRTOLC10 and BRTOLC9. The instrument now moves to "train on line coming."

When the train clears the fouling track, the track relay picks up again, but without causing any effect except the release of relay XTPR.

The signalman at B should now clear his home signal HB (see Figure 1), which picks up relay HSS over the reverse contact HBR on the home signal lever, and which sticks up over back contact 4 of relay YTHSSP (corresponding to relay XTHSSP at point A) and front contact 4 of HSS.

When the train reaches the track section BXT the track relay releases so energising relay YTPR (corresponding to relay XTPR at A). The home signal may now be replaced at any time; there is no lock on the home signal lever.

When the train clears the track section BXT the track relay picks up and opens the circuit for relay YTPR. As this relay has a delayed release, a circuit is made over front contact 1 of YTR, front contact 2 of relay HSS, front contact 1 of relay YTPR, coil of relay YTHSSP to negative, in sufficient time for relay YTHSSP to pick up and stick up over back contact 3 of BTB and front contact 1 of YTHSSP. Energisation of this relay breaks the stick circuit for relay HSS at back contact 4. Should the home signal be restored to normal relay BTB now picks up over a circuit from positive, front contact 3 of relay BRTOLC, back contact 3 of relay HSS, normal contact on levers of signals HB, front contact 1 of relay YTHSSP, coil of relay BTB, back contacts 1 of relay BTC and BTCR, "code cut out" 16 to negative, and sticks up over the relay 4B released as usual. The release of relay YTHSSP is proved in the transmission at back contact 3.

Relay ARLB will pick up in response to the transmission and stick up over back contact of ATLBK11 and front contact 4 of ARLB.

A circuit is now completed from positive through back contact ALCS1, normal contacts S6N and S5N on levers of signals 6 and 5, front contact ARLB3, coil of ATLBK, back contacts ATC7 and ATCR7, "code cut out" button over relay back contact 4B4. This relay opens 16 to negative, the stick circuit being as usual the circuit for relay ARLB at back contact 11, so releasing it.

A slow release feature is provided on relay ATLBK, to enable the relay to hold up for sufficient time at the completion of the transmission, for the latch circuit for relay ATOLG to

be made over front contacts 4B1 and of ATLBK8 (see Figure 10). The release of relay ARLB is proved in the transmission at back contact 1.

Release of relay ATOLG breaks the circuit to the instrument indicator and allows it to return to the "line closed" position.

Relay BRLBK is now energised at B and sticks up over a KRD contact on the release lever K. This releases the reverse lock on the release lever (see Figures 11 and 11a), allowing this to be restored so de-energising relay BRLBK. Also, when relay BRLBK is energised, it completes the circuit for the latch coil of relay BRTOLC at front contact BRLBK4, so de-energising relay BRTOLC and returning the instrument to normal or "line closed."

The prevention of opposing moves at the points A and B is effected as follows:

The release lever K must be in its normal position to pick up relay ATILC in order to initiate a code for "is line clear," but it is also required in the reverse position in order to send the "line clear" code, and a glance at the circuits will show that it cannot be returned to its normal position until relay ARLBK picks up to make its front contact 8, in order that the reverse lock KK on the release lever K may be energised to permit the lever to be returned to normal.

We now have the condition that lever K has been reversed in order to send "line clear" to B and that it cannot be returned to normal (a necessary condition for the sending of "is line clear") until relay ARLBK is energised. It will also be appreciated that B cannot send "line clear" to A until he receives "is line clear" from A; since the circuit for relay BTLC at B is broken at a front contact of BRILC.

Now relay ARBLK picks up only in response to a code sent from B to prove that "line closed" has been received from A and, as "line closed" is sent from A to B when the train has cleared the section, it follows that, once A has operated his release lever to send "line clear" to B, he cannot return it to normal, and therefore cannot send "is line clear" to B, until the train has passed right through the section. It is therefore ensured that "line clear" cannot be given for opposing moves.

As regards following moves the prevention of these is effected as follows:

When A receives "line clear" from B, relay ARLC picks up and sticks up over NB contacts on the two starting signal levers S5 and S6. When an attempt is made to operate the lever to clear say signal 6, the lever can be moved to its (B) position where it is held by the lever lock KSS6 (see Figures 12 and 12a). There is now a circuit over front contact ARLC4 to energise the lever lock, and the lever can be operated. Once it is taken past the (B) position, relay ARLC releases. Relay ARLC can now be picked up only on the receipt of another "line clear" code from B, so that, once the signal lever is replaced, it cannot again be pulled until permission is received from B.

In the event of the "is line clear" button 1 at points A and B being operated so nearly at the same time that the transmitter relays BT at each point pick up simultaneously, the system is so arranged that under these conditions the code from point A takes precedence.

When the BT relays pick up simultaneously at the points A and B, the two batteries ALB and BLB are connected in series and the two BL relays from point A takes precedence.

lays pick up on double current. But relay QR at B releases some time before relay SR at A due to their difference in slow release, hence when QR releases it opens the circuit for BT at B, but BT releasing only cuts cut battery BLB, so that the BL relays are maintained energised over the front contact of BT at A receiving energy from battery ALB.

Thus at point B, front contacts 3 and 6 of relay BT are open, while front contact 2 of relay BL remains closed; hence the circuit for relay M is open and this relay releases at B and relay R picks up.

At point A however, both relays BT and BL remain energised until slow release relay SR releases, so that relay M remains energised.

It will be understood that the invention is not limited to the particular system above described and illustrated by way of example which may be varied and amplified in many respects without exceeding the scope of the invention.

Having now described our invention, what we claim as new and desire to secure by Letters Patent is:

- 25 1. In a signal control system for a stretch of single railway track in which signals are located at opposite ends of the stretch for governing traffic movements over the stretch, the combination comprising, manual control apparatus located adjacent each of the opposite ends of said stretch each including a manually controllable contact device freely operable at any time and a second manually controllable contact device having a normal and a reverse position and said second contact device having a normal lock for locking said second contact device in the normal position if said normal lock is deenergized, a pair of control conductors extending between the opposite ends of said stretch, means controlled by operation of one of said first contact devices if the adjacent second contact device is in its normal position for transmitting a code over said conductors to the apparatus at the opposite end of said stretch for effecting an indication "is line clear" at said opposite end of the stretch and for energizing the lock for the second contact device at said opposite end of the stretch, means controlled by the second contact device at said opposite end of the stretch if then operated to its reverse position for transmitting a code over said conductors to the first end of the stretch for effecting a "line clear" indication at the first end of said stretch, and means for clearing a signal at the first end of said stretch if the "line clear" indication has been received.

2. In a signal control system for a stretch of railway track in which signals are located at opposite ends of the stretch for governing traffic movements over the stretch, the combination comprising, two offices one adjacent each end of said stretch connected by two line wires and each comprising code transmitting apparatus and code responsive apparatus, a first and a second manually controllable contact device for each of said offices each having a normal and a reverse position, means controlled by each of said first contact devices when operated to its reverse position if the associated second contact device is in the normal position for effecting operation of the code transmitting apparatus at its office to transmit a first code over said line wires, means controlled by the code responsive apparatus at the other office in response to said first code for displaying the indication "is line clear," means controlled by the code responsive apparatus at said

other office in response to said first code and controlled by the associated second contact device upon being operated to its reverse position for effecting operation of the associated code transmitting apparatus to transmit a second code over said line wires, and means controlled by the code responsive apparatus at the first office in response to said second code for displaying the indication "line clear received."

3. In a signal control system for a stretch of railway track in which signals are located at opposite ends of the stretch for governing traffic movements over the stretch, the combination comprising, two offices one adjacent each end of said stretch connected by two line wires and each including apparatus for transmitting codes over said line wires to the other office and for responding to codes transmitted over said line wires from the other office, a first and a second manually controllable contact device for each of said offices each having a normal and a reverse position, means controlled by each of said first contact devices if operated to its reverse position while the associated second contact device is in the normal position for effecting operation of the apparatus at its office to transmit a first code over said line wires, means controlled by the apparatus at the other office in response to said first code for displaying the indication "is line clear" and for transmitting a second code over said line wires if the associated second contact device is operated to its reverse position, means controlled by the second contact device at said other office upon being operated to its reverse position for displaying the indication "line clear sent," and means controlled by the apparatus at the first office in response to said second code for displaying the indication "line clear received."

4. In a signal control system for a stretch of railway track in which signals are located at opposite ends of the stretch for governing traffic movements over the stretch, the combination comprising, two offices one adjacent each end of said stretch connected by two line wires, a first and a second manually controllable contact device at each office each having a normal and a reverse position, means controlled by each of said first contact devices if operated to its reverse position and if the associated second contact device is in the normal position for transmitting a first code over said line wires, means at the other office responsive to said first code for displaying the indication "is line clear" and for transmitting a second code over said line wires if its associated second contact device is operated to its reverse position, and means at the first office responsive to said second code for displaying the indication "line clear received."

5. In a signal control system for a stretch of railway track in which signals are located at opposite ends of the stretch for governing traffic movements over the stretch, the combination comprising, two offices one adjacent each end of said stretch connected by two line wires, a first and a second manually controllable contact device at each office each having a normal and a reverse position and said second contact device having a normal lock for locking said second contact device in its normal position when the corresponding lock is deenergized, means controlled by each of said first contact devices if operated to its reverse position and if the associated second contact device is in the normal position for transmitting a first code over said line wires, means at the other office responsive to said first code

for displaying the indication "is line clear" and for energizing the normal lock for the associated second contact device, means at said other office controlled by the associated second contact device upon being operated to its reverse position for transmitting a second code over said line wires, and means at the first office responsive to said second code for displaying the indication "line clear received."

6. In a signal control system for a stretch of railway track in which signals are located at opposite ends of the stretch for governing traffic movements over the stretch, the combination comprising, two offices one adjacent each end of said stretch connected by two line wires, a first and a second manually controllable contact device at each office each having a normal and a reverse position and said second contact device having normal and reverse locks for locking said second contact device in its normal and reverse positions respectively when the corresponding lock is deenergized, means controlled by each of said first contact devices if operated to its reverse position and if the associated second contact device is in the normal position for transmitting a first code over said line wires, means at the other office responsive to said first code for energizing the normal lock for the second contact device at said other office, means at said other office controlled by the associated second contact device upon being operated to its reverse position for transmitting a second code over said line wires, means controlled manually and by said second code for clearing a signal adjacent the first office, means responsive to a train upon passing said signal for transmitting a third code over said line wires, and means controlled in part by said third code for energizing the reverse lock for the second contact device at said other office.

7. In a signal control system for a stretch of railway track in which signals are located at opposite ends of the stretch for governing traffic movements over the stretch, the combination comprising, two offices one adjacent each end of said stretch connected by two line wires, a first and a second manually controllable contact device at each office each having a normal and a reverse position and said second contact device having normal and reverse locks for locking said second contact device in its normal and reverse positions respectively when the corresponding lock is deenergized, means controlled by each of said first contact devices if operated to its reverse position and if the associated second contact device is in the normal position for transmitting a first code over said line wires, means at the other office responsive to said first code for energizing the normal lock for the second contact device at said other office, means at said other office controlled by the associated second contact device upon being operated to its reverse position for transmitting a second code over said line wires, means controlled manually and by said second code for clearing a signal adjacent the first office, and means controlled by a train upon having passed through a short track section adjacent each end of said stretch for energizing the reverse lock for the second contact device at said other office.

8. In a signal control system for a stretch of railway track in which signals are located at opposite ends of the stretch for governing traffic movements over the stretch, the combination comprising, two offices one adjacent each end of said stretch connected by two line wires, a first

and a second manually controllable contact device at each office each having a normal and a reverse position, means controlled by each of said first contact devices if operated to its reverse position and if the associated second contact device is in the normal position for transmitting a first code over said line wires, means at the other office controlled by said first code and by operation of the second contact device at said other office to its reverse position for transmitting a second code over said line wires, a manually operable signal control device at the first office having a normal lock which if deenergized locks said signal control device in a normal position, means controlled by said second code for energizing the normal lock for said signal control device, and means controlled by operation of said signal control device to a reverse position for clearing a signal at the first office and for cancelling the control by said second code so that if the signal is then returned to stop it cannot again be cleared until said second code is again transmitted from said other office.

9. In a signal control system for a stretch of railway track in which signals are located at

opposite ends of the stretch for governing traffic movements over the stretch, the combination comprising, two offices one adjacent each end of said stretch connected by two line wires, a first and a second manually controllable contact device at each office each having a normal and a reverse position, means controlled by each of said first contact devices if operated to its reverse position and if the associated second contact device is in the normal position for transmitting a first code over said line wires, means at the other office controlled by said first code for transmitting a second code over said line wires if the second contact device at said other office is operated to its reverse position, means controlled manually and by said second code for clearing a signal adjacent said first office, means responsive to a train upon passing said signal for displaying an indication "train on line going" at the first office and for transmitting a third code over said line wires, and means controlled by said third code for displaying an indication "train on line coming" at said other office.
